UNITED STATES PATENT OFFICE.

LEON E. LA BOMBARD, OF WEST NEWTON, AND MELVIN H. SIDEBOOTHAM, OF NEWTONVILLE, MASSACHUSETTS, ASSIGNORS TO SPECIALTY AUTOMATIC MACHINE COMPANY, OF CHELSEA, MASSACHUSETTS, A CORPORATION OF MASSACHUSETTS.

MACHINE FOR MAKING GARMENT CONTAINERS.

Application filed April 1, 1927. Serial No. 180,153.

This invention relates to the manufacture of that type of envelopes commonly known as shirt holders or laundry envelopes and which usually consist of a thin and somewhat transparent paper front member and a relatively thick pasteboard back member, the two members being adhesively connected at their side edges.

One of the objects of our present invention is to produce a machine which will automatically and rapidly produce, from two rolls of paper and pasteboard, completed envelopes or containers of the character described.

Another object of the invention is to produce the containers with printed matter borne thereon.

Another object is to produce the containers with their thin or front members having transverse edges doubled or folded to reinforce them.

Another object is to produce containers which are automatically stiffened longitudinally by the insertion of garments between the front and back members.

Another object is to produce the containers with the side edges of the thick members softened so that the marginal portions of the thin members which enclose said softened edges will not be ruptured.

With the above and other hereinafter-explained objects in view, the invention consists in the construction and combination of parts substantially as hereinafter described and claimed.

Of the accompanying drawings:

Figures 1, 2, 3, 4 and 5 are plan views which, taken together, illustrate the entire machine with the exception of the final end of the belt and other mechanism which receives or stacks the output of the machine.

Figure 1^a is a detail perspective view looking in the direction of the arrow 1^a, Figure 1.

Figure 2^a represents a section on line II^a of Figure 2 on a larger scale.

Figure 4^a represents a section on the line IV^a of Figure 4 on a larger scale.

Figure 6 is a perspective view of some of the parts shown in Figure 3.

Figure 7 represents a section on line VII of Figure 3 on a larger scale.

Figure 8 represents a section on line VIII of Figure 4 on a larger scale.

Figure 9 represents a section on line IX of Figure 5 on a larger scale.

Figure 10 is a detail perspective view looking in the direction of the arrow 10 of Figure 4.

Figure 11 represents a section of the adjacent members shown in Figure 10.

Figure 12 is a perspective view of the product of the machine.

Similar reference characters indicate similar parts or features in all of the views.

To facilitate an understanding of the details of the machine, a preliminary brief description of its operation will be given:

A roll of material such as chipboard is mounted at one end of the machine and the web or strip is drawn therefrom and fed to mechanism which cuts it into sections of exact length. While on its way to be cut, its edges are slightly pressed inward to soften them, and near its edges longitudinal creases are formed. At a farther point of the machine glue is applied to the under surface of each section, near its side edges and for a distance less than the length of the section. Then a roll of thin paper, such as tissue, is cut into sections of less length than the thick sections, one edge of each thin section is transversely doubled or folded, each thin section is applied flat on a thick section and the edges of the thin section folded over the side edges of the thick section and pressed against the portions of the thick section having the stripes of glue. The thin and thick sections are so assembled that at one end their edges are accurately alined, a portion of each thick section at the other end being exposed owing to its being longer than its superposed thin section. Before issuing from the machine, each envelope or container is printed.

An important feature of the invention is that all of the above-described steps of the operation occur while the webs of material or the sections cut therefrom are traveling, the result being a very high speed of production.

Referring now to the structure of the machine, a suitable frame therefor is illustrated as a whole at 25. At one end (Fig.

- 1) a supply roll of the web *a* which, in the present use of the machine consists of fairly thick paper or pasteboard known as chip-board, is mounted on a shaft 26. Said roll, 5 or the web drawn therefrom, is prevented from shifting laterally and is held under brake mechanism by suitable means such as that disclosed in our application filed December 6, 1926, Serial No. 152,749. The 10 web from the roll passes through suitable tension mechanism and is drawn to the presently described mechanism by several pairs of driven rolls at different locations along the machine, one pair of said rolls being indicated at 27, 28, the upper one, 27, being 15 shorter than the lower one 28.

On its way to the rolls 27, 28, the web is creased at *a'* by means of converging creasing disks 29 of a well-known type mounted on a 20 cross bar 30. Directly under the creasers is a roll 31 which supports the web against the pressure of the creasers. This creasing has a special object which will be explained hereinafter.

25 The reason for the rolls 27, 28, being of different lengths as above mentioned is to provide a support 28 for the full width of the web, while the roll 27 is of such length that it will not bear on and flatten out the 30 creases *a'*.

Supplementary web-feeding means consists of upper disks 32 carried by shaft 33 and having a width to bear only on the marginal portions of the web outside of the 35 creases, said disks cooperating with similar lower disks or a roll.

The web leaving the feeding rolls and disks passes onto a plate or table 34 (Figs. 1, 2 and 2^a) at which point the marginal 40 portions of the web are temporarily folded up and in to somewhat "break" the web on its crease lines. This is effected by a pair of folder strips 35 mounted on the plate 34, the inner faces of said strips being shaped to 45 bend or fold the marginal portions of the web inward. To hold the middle portion of the web flat on the plate, two pressing or guiding strips 36 having thin extensions 37 (Fig. 2) are mounted on cross rods 38.

50 Before the web is cut into sections as hereinafter described, it is returned to flat condition; that is, its temporarily folded margins are laid back flat outwardly in order to enable proper transverse cutting to 55 be effected. And since the material of the web is not of a strong character, it is essential that the inward and the return outward bends or folds shall be very gradual so that the margins will not be torn due to the 60 slight stretching effect of the inward folding. Therefore, as illustrated, the plate 34, and the plate 39 over which the web travels while returning to flat condition, are quite long, and the distance from the point where 65 the margins are first turned up to the point

where they are returned to flat condition is considerable, in order to effect a quite gradual inward bend and a gradual outward or return bend.

Between the two plates 34, 39, are guiding rolls the upper one of which is illustrated at 40 carried by a shaft 41, the said rolls preventing lateral movement of the web which is being temporarily folded. 70

Continued travel of the web *a* to the cutting mechanism which severs it into sections is effected by feeding rolls 42, 42' (Figs. 3 and 7). Just before reaching said rolls the web passes under a plate 43 supported by a bridge piece 44, said plate 43 being laterally tapered. The object or function of said plate 43 is to render it certain that if an edge portion of the web should happen to be torn, such tear will not interfere with the operation of the machine. That is, any torn edge will slide along the tapered edges of the said plate and be guided or laid out flat. 80

The next operation of the machine is to cut the web *a* having its creases *a'* into sections *a''* (Figs. 3 and 7). This is effected by a suitable cutting mechanism comprising, in the present instance, upper and lower rolls 45, 46, the upper roll 45 carrying a cutting blade 47. Each section cut from the web is immediately pulled along or advanced a short distance by the contact therewith of one or more segments 48 carried by a shaft 49 (Figs. 3, 6 and 7), said shaft and its segments being rotated by gearing illustrated but not necessary to describe in detail, such rotation being at such speed and in such timing that each section *a''* is separated sufficiently from the web to enable one of the pins 50 carried by an endless chain 51 to catch up to the rear edge of the section and push it along. Said chain at one end is mounted on a sprocket 52 (Fig. 7) carried by the shaft 53 which also carries disks below and cooperating with the segments 48. 100

Each section being pushed along by a pin of the chain is guided to and beyond gluing devices presently described, by angular side guides 54 having supporting pins 55 (Fig. 6) rising from blocks 56 mounted on tie rods 57 of the frame 25. Preferably, also, longitudinal strips 58 are employed, supported by cross bars 59 which connect the two guide bars 54. 110

Suitably supported by the frame of the machine is a glue box 60 (Fig. 3). A shaft 61 extends through the glue box and carries two disks 62. Said shaft is driven by a chain 63 and other gearing at a speed of one revolution for each passing pasteboard section *a''*. The reason for this will be presently explained. 125

The tops of the glue disks 62 are at such points of elevation or in such planes, that 130

the margins of the sections a^2 would not receive glue therefrom unless said margins are pressed down into contact with said glue disks. To press said margins down at just the right times and for the proper lengths of said times, the following mechanism is provided:—A pair of small rolls 64 (Figs. 3 and 6) are carried by arms 65 of a rock shaft 66 supported by frame posts 67. Said shaft 66 has an arm 68 bearing on a cam 69 carried by shaft 61 and has another arm 70 to which a spring 71 is connected. The spring 71 acts to cause the rolls 64 to press the margins of each passing pasteboard section down into contact with the glue disks so long as such pressing is permitted by the low portion of the cam 69. Then when the high portion of the cam is passing under the arm 68 the depressing rolls 64 are lifted. The object of this structure is to avoid the application of any glue to a passing section a^2 excepting in the positions and for such lengths of stripes of glue as to equal the length and the proper positioning of the tissue section b' which is to be adhesively connected to each passing section a^2 at a farther point of the machine as presently described. It will now be understood why the shaft 61 which carries the cam 69 as well as the glue disks 62, revolves once for each passing section a^2 . At this point it is desirable to refer to the fact that each finished garment container consists of a stiff back member a^2 and a thin or tissue front or face member b' which latter is considerably shorter than the back member (see Figure 12). Therefore, if glue were to be applied to the back members a^2 along portions which are not later covered by the marginal portions of the front members b' as presently described, the uncovered or exposed glue would cause the products of the machine to stick together after issuing from the machine. This feature enables the machine to be operated at a speed which is in no way limited by any necessity for effecting any drying before stacking the containers.

It is to be understood, of course, that the high and low portions of the cam 69 are of such relative peripheral lengths that the rolls 64 of the arms 65 depress the margins of each passing section a^2 into contact with the glue disks only long enough to effect the application to each section of two stripes of glue having the right length and the correct longitudinal locations to be just covered by the folded marginal portions of a tissue member b' which marginal portions are folded over the edges of the section a^2 and glued to the rear surface thereof.

The sections a^2 which are pushed along by the pins 50 of the chain 51 are supported by suitable means such as strips or plates 72, 113, (Figs. 3, 6 and 8).

The chain 51 has been referred to as mounted at one end on a sprocket 52 (Fig. 7). At its other end it is mounted on a sprocket 74, carried by shaft 75 (Fig. 8). The pins 50 of said chain bring the sections a^2 successively to the position where a section of tissue paper is applied to and affixed to each section a^2 .

The mechanism for feeding a web of the tissue paper and cutting into the required sections will now be described. Said mechanism includes a supporting shaft 80 for a roll of the thin paper b (Fig. 4). The web b passes over a roll 81 (Figs. 4 and 8) carried by arms 82 of a shaft 83, said shaft 80 having another arm 84 to which a spring 85 is connected to effect pressure of the roll 81 against the upper one of a pair of driven rolls 86, 87, which grip and feed the web. The web is cut into sections b' by a blade 88 carried by the roll 87, and each section is moved by the said rolls 86, 87, onto table strips 89 supported by cross bars 89, and then passes to the nip of rolls 90, 91. The web b and sections b' are illustrated by heavy black lines in the interest of clearness. The material is, in practice, very thin.

To ensure proper successive travel of the sections b' to the rolls 90, 91, belts 93 are employed, mounted on and driven by small pulleys 94, the said belts traveling between the table strips 89. To hold the sections in contact with the carrier belts 93, guide strips 95, and presser bars 96 with balls or rolls therein, are employed, said strips and bars being supported by a tie bar 97.

In the use of garment containers of the character referred to and such as illustrated by Figure 12, it is customary to lay a folded garment on the exposed or uncovered portion of the thick back member a^2 and push it into the container past the transverse edge of the thin front member b' . As said transverse edge is liable to become torn by this operation, means are provided for reinforcing it (see, the broken out portion of Figure 12), doing this before the two members are assembled. This operation is performed on that edge of each section b' which is the first to reach the nip of the rolls 90, 91, (see Figs. 8, 10, and 11). A blade 98 projects from a rod 99 mounted to rock in a transverse socket in the periphery of the roll 90, said rod having at one end an arm 100 to which two springs 101 are connected and which permit the blade carried by the rod to yield forward or back relatively to the direction of rotation of the roll. Another blade 102 projects from a rod 103 mounted to rock in a transverse socket in the periphery of the lower roll 91, said rod having at one end an arm 104 which is maintained by a spring 105 in contact with a cam 106 carried by a fixed sleeve 107 in which the shaft of the roll 91 rotates. An idle roll 108

108 is carried by a pair of arms 109 of a rock shaft 110 which has another arm 111 to which a spring 112 is connected, said spring serving to maintain the idle roll 108 in yielding contact with the roll 91.

The timing of operation of the mechanism is such that the advancing edge of each section b' reaches the nip of the rolls 90, 91, just before said rolls arrive at the point of revolution illustrated by Figure 11, so that, as the rolls reach said illustrated positions, the blade 98 doubles or folds the paper down alongside of the blade 102, close to or near the edge of the paper, and then the continued rotation of the rolls releases the folds from the two temporarily overlapping blades 98, 102, and as said advancing edge passes the idle roll 108 the latter completes the fold. The timing of operation is such that the front edge of the stiff member a^2 arrives under the roll 91 (see Fig. 8) far enough in advance of the arrival of the thin member b' on top of the stiff member, to leave the forward end of the member a^2 un-covered by the member b' (see Fig. 12), and so that the rear end edge of the member b' exactly registers with the rear end edge of the member a^2 . This accurate registration is also illustrated in Figure 8.

Each section a^2 passes from the plate 72 to a plate 113, said plates being supported by cross bars 114, with a space between them to accommodate an idle roll 115 carried by arms 116 of a rock shaft 117 another arm 118 of which has a spring 119 connected to it. The roll 115 cooperates with the roll 91 in ensuring travel of the superimposed sections a^2 , b' , to position to be engaged by lower and upper belts. In the present machine there are three lower belts 120 mounted on pulleys 121, 122, carried by shafts 123, 124, (compare Figs. 8 and 9), and three upper belts 125 mounted on pulleys 126, 127, carried by shafts 128, 129. Suitable pressure rolls are illustrated at 130 (Fig. 8). The relationship of the six belts just referred to is illustrated in Figure 4^a. Bearing on the two outer upper belts 125 are rolls 131 which are carried by arms 132 (Fig. 4) supported by a cross strip 133 mounted on a longitudinal strip 134 suitably supported by the frame of the machine. Said rolls 131 are for the purpose of firmly pressing and holding the superimposed members a^2 , b' , together during the operation of folders 135 (Figs. 4 and 4^a) which are supported by transverse frame bars one of which is illustrated at 136. Said folders are so shaped that their inner surfaces act on the side margins of each thin section b' (the sections b' being wider than the sections a^2) to fold said side margins over the side edges and against the under surface of the marginal portions of the section a^2 where the stripes of glue were applied by the glue disks 62 as

hereinbefore described. These marginal portions then immediately pass pressing rolls 137 carried by arms 138 of a cross bar 139 (Figs. 5, 9 and 4), and thereby the two sections or members are firmly united. 70

For convenience of description, the now completely assembled sections or members a^2 , b' , will be referred to as the container or envelope.

The belts 120, 125, deliver each container onto strips 140 supported by cross bars 141 (Figs. 5 and 6) and between side guides or margin strips 142, and the container arrives against a stop 143 which temporarily arrests it. Said stop is carried by 80 an arm 144 of a rock shaft 145 (Fig. 9), said shaft having another arm 146 provided with a roll 147 which is acted upon by a cam 148 of a shaft 149, to cause the stop 143 to rise 85 and permit it to fall by its weight or a suitable spring. The shaft 149 also carries a disk 150.

Above the shaft 149 is a shaft 151 carrying a segment 152. The timing is such that the 90 container arrives against the raised stop while the segment is approaching the position shown in Figure 9, and then the stop is lowered as, or just after, the segment 152 contacts with the container. Of course the 95 structure may permit some slipping of the segment if it contacts with the container before the latter is released by the stop. As soon as released, the container is advanced over the table strips 140 by the segment, to 100 the printing mechanism the operation of which is so timed as to apply the desired laundry or other printed matter to the surface of the thin member b' in accurate position longitudinally thereof. 105

The printing mechanism includes a platen cylinder 153 carried by shaft 154, and a printing cylinder 155 carried by shaft 156. Marginal pressing rolls 157 are carried by arms 158 of a rock shaft 159 having another 110 arm 160 to which a spring 161 is connected. Some of the usual inking rolls are illustrated at 162, and an ink-supply is indicated at 163 in Figure 5.

The complete and printed containers are 115 delivered to a suitable stacking belt 164 having a row-holding roll 165 above it.

Referring to Figure 12, it will be seen that the thin tissue member b' is so applied or connected to the thick back member a^2 so as to be taut laterally. In practice, the machine delivers the containers with the two members substantially in contact throughout their areas. In said Figure 12 a slight space is indicated between the two members, such illustration being for the purpose of clarifying the following description of the reason for the crease lines a' :

Owing to the taut condition of the thin member, the lateral pull or strain created 130

when a garment is inserted between the two members deflects the marginal portions of the thick member out of a flat plane, the crease lines a' serving somewhat as hinges.

5 There is no objection to the containers being quite flexible in any direction, when not filled, but longitudinal stiffness is desirable when they are filled, as such stiffness aids in preserving the contained shirts or other 10 articles in smooth condition. Owing to the presence of the creases a' , and the taut condition of the member b' , the act of inserting a garment in the container automatically converts it to condition resembling a trough 15 which greatly increases its longitudinal stiffness.

In view of the fact that the paper employed for the front members b' is not strong, the extreme edges of the members a' 20 would be liable to cut through or tear the thin paper where it passes over said extreme edges, if no provisions were made to prevent it. Therefore the present machine is provided with means for softening the edges 25 of the thick material by exerting inward pressure thereon so as to somewhat scrape or round said edges. This is done by the machine before the web a is cut into sections.

Referring to Figures 1 and 1^a, the table 30 34 has fixedly mounted thereon two edge softeners, each consisting of a piece of metal bent to provide a base 166 and an upper part 167, the latter having a spring strip 168 secured thereto as by a rivet 169. Said two 35 attachments are so mounted that their bent portions are inclined toward each other (Fig. 1), and they are so spaced apart that the inner surfaces of the bends, where the web a issues from between them, somewhat 40 restrict free passage of the web. The two spring strips 168 hold the passing web down on the bases 166 so that the edges of the web are slightly deflected out of a flat plane in the effort to pass the slightly restricted 45 space between the two attachments, resulting in so softening the extreme edges of the web that the sections thereof, when they become members of complete containers at another point of travel through the machine, will not 50 cause rupture of the portions of the thin members which are tautly folded thereover.

As the operation of the machine as a whole has been preliminarily described, and the operations of the several portions of the 55 machine have been described in connection with references to the details thereof, further description of the operation of the machine is unnecessary.

Having now described our invention, we 60 claim:

1. A machine of the character described, comprising means for drawing a plurality of webs of material from supply rolls, means for independently converting each of 65 the webs into sections, and means for as-

sembling the sections with their margins connected together.

2. A machine of the character described, comprising means for feeding webs of relatively thick and thin material, and means 70 for independently converting each of the webs, while traveling into sections, said machine including means for adhesively connecting marginal portions of the thick and thin sections of material. 75

3. A machine of the character described, comprising means for feeding a plurality of webs of material, means for independently converting each of the webs into sections, means for assembling the sections with their 80 margins connected together, and means for printing one of said layers.

4. A machine of the character described, having means for progressively severing a plurality of webs into sections of different 85 lengths, and means for superposing the sections and connecting them together at opposite margins.

5. A machine of the character described, having means for progressively severing a 90 plurality of webs into sections of different lengths, and means for assembling the sections in pairs and adhesively connecting opposite marginal portions thereof.

6. A machine for making garment containers, comprising means for feeding a thick web and a thin web, means for independently cutting each web into sections, and means for marginally connecting each thin section to a thick section. 95 100

7. A machine for making garment containers, comprising means for feeding a thick web and a thin web, means for independently cutting each web into sections, means for longitudinally creasing the thick 105 web before it is cut into sections, and means for marginally connecting each thin section with a thick section.

8. A machine for making garment containers, comprising means for feeding a 110 thick web and a thin web, means for independently cutting the webs into sections, means for folding the side margins of each thin section over the side edges of a thick section, and means for adhesively securing 115 said folded margins.

9. A machine for making garment containers, comprising means for feeding a thick web and a thin web, means for independently cutting the webs into sections, 120 means for assembling each thin section with a thick section in longitudinal registered relationship, and means for connecting the side margins of the assembled sections.

10. A machine for making garment containers, comprising means for feeding webs of relatively thick and thin paper, means for cutting both webs into sections, means for folding a transverse edge of each thin section to reinforce it, and means for adhesively con- 125 130

necting the side margins of each thin section to the side margins of a thick section.

11. A machine for making garment containers, comprising means for feeding webs of relatively thick and thin paper, means for cutting the webs into sections, means for folding the side margins of each thin section over the side edges of a thick section, and means for adhesively securing the said folded margins to the rear surface of the thick section.

12. A machine for making garment containers, said machine having means for feeding a thick web and a thin web, means for longitudinally creasing the thick web, means for flexing the margins of the thick web on its crease lines, means for independently cutting each web into sections, and means for marginally connecting each thin section to a thick section.

13. A machine for making garment containers, said machine having means for feeding a thick web and a thin web, means for longitudinally creasing the thick web, a pair of folder strips in position to bend the margins of the thick web inward, means for returning said margins to outward flat condition, means for independently cutting each web into sections, and means for marginally connecting each thin section to a thick section.

14. A machine for making garment containers, said machine having means for feeding a thick web and cutting it into sections, means for feeding a thin web and cutting it into sections of less length than the thick sections, means for applying to the thick sections stripes of glue limited in length to the length of the thin sections, and means for assembling the thick and thin sections with marginal portions of the thin sections overlying the glue stripes of the thick sections.

15. A machine of the character described, said machine having means for feeding webs of relatively thick and thin paper, means for cutting the webs into sections, a pair of rolls for advancing each thin section, said rolls having cooperating blades to fold a transverse edge of each thin section, and means for adhesively connecting the side margins of each thin section with the side margins of a thick section.

16. A machine for making garment containers, said machine having means for feeding a thick web and a thin web which is wider than the thick web, means for independently cutting the webs into sections, means for applying glue to marginal portions of each thick section, and means for folding marginal portions of each thin section over the edges of a thick section and against the glue-bearing areas of the latter.

17. A machine for making garment containers, said machine comprising means for

feeding a thick web and a thin web, means for inwardly compressing the edges of the thick web to soften said edges, means for independently cutting each web into sections, and means for folding the marginal portions of each thin section over the softened edges of a thick section.

18. A machine of the character described, comprising means for feeding a web of stiff paper material and cutting it into sections, means for longitudinally creasing said web and softening its edges on its way to be cut, means for applying glue to each section near its side edges, means for feeding a web of thin paper and cutting it into sections of less length than the length of the stiff sections, and means for applying each thin section flat on a stiff section with the margins of the thin section enclosing the edges of the stiff section.

19. A machine of the character described, comprising means for feeding a web of stiff paper material and cutting it into sections, means for longitudinally creasing said web and softening its edges on its way to be cut, means for applying glue to each section near its edges, means for feeding a web of thin paper and cutting it into sections of less length than the length of the stiff sections, means for applying each thin section flat on a stiff section with the margins of the thin section enclosing the edges of the stiff section, mechanism for printing one of the members of the assembled sections, and means for temporarily arresting the assembled sections on their way to the printing mechanism to effect accurate location of the printed matter.

20. A machine for making garment containers, comprising means for feeding a thick web and a thin web, means for independently cutting each web into sections, means for longitudinally creasing the material of the thick web, and means for marginally connecting each thin section with a thick section.

21. A machine of the character described, comprising means for feeding a web of stiff paper material and cutting it into sections, means for softening the edges of the stiff material, means for applying glue to each section near its side edges, means for feeding a web of thin paper and cutting it into sections, and means for applying each thin section flat on a stiff section with the margins of the thin section enclosing the softened edges of the stiff section.

22. A machine of the character described, comprising means for feeding a web of stiff paper material and cutting it into sections, means for longitudinally creasing said web and softening its edges, means for applying glue to each section near its side edges, means for feeding a web of thin paper and cutting it into sections of less length than the

length of the stiff sections, means for applying each thin section flat on a stiff section with the margins of the thin section enclosing the edges of the stiff section, mechanism 5 for printing the assembled sections, and means for temporarily arresting the assembled sections on their way to the printing mechanism to effect accurate location of the printed matter.

10 23. A machine for making garment con-

tainers, said machine comprising means for assembling thick and thin members with their marginal portions connected, the said machine having means for operating on the edges of the thick members to soften said 15 edges.

In testimony whereof we have affixed our signatures.
